UNITED STATES PATENT OFFICE.

CHARLES E. CHURCH, OF BOSTON, MASSACHUSETTS, ASSIGNOR TO THE
HANCOCK INSPIRATOR COMPANY, OF SAME PLACE.

EJECTOR.

SPECIFICATION forming part of Letters Patent No. 405,992, dated June 25, 1889.

Application filed July 17, 1888. Serial No. 280,200. (Model.)

To all whom it may concern:

Be it known that I, CHARLES E. CHURCH, of Boston, in the county of Suffolk, and in the State of Massachusetts, have invented certain new and useful Improvements in Ejectors; and I do hereby declare that the following is a full, clear, and exact description thereof, reference being had to the accompanying drawings, in which—

10 Figure 1 shows a vertical longitudinal section of my improved apparatus; Fig. 2, a detail perspective view showing a portion of the apparatus shown in Fig. 1, and Fig. 3 shows a modified construction of the apparatus 15 shown in Fig. 1. Fig. 4 shows in vertical longitudinal section another modification of the construction shown in Fig. 1.

Letters of like name and kind refer to like parts of the apparatus.

20 My invention relates to that class of jet apparatus known as "ejectors" or "lifters," and has for its object to increase the amount of fluid delivered therefrom without at the same time impairing the vacuum which the apparatus would otherwise create and maintain; and it consists in the construction and arrangement of a supplemental inlet to the combining and delivery tube of the apparatus 25 communicating with the suction-pipe or water-chamber and with the interior of the tube at or near its throat with a valve adapted to permit the flow of fluid from the said chamber to the interior of the tube, but which will prevent reflux of the fluid from the tube into 30 the water-chamber, and in means provided whereby said valve will close said inlet automatically whenever the pressure within said tube at the point therein where the said inlet communicates therewith is greater than the 35 pressure in the water-chamber, and which will open automatically when the pressure in the tube is less than the pressure within the said chamber.

In Fig. 1 of the drawings, A is the casing, 45 externally screw-threaded at its lower end and at C' for connection with the delivery and suction pipes, respectively, and internally threaded at its upper end for the bonnet B, (more clearly shown in Fig. 3,) also 50 externally threaded for connection with the steam-space of the boiler. Within the casing

the usual water-chamber is formed by the partitions P T'. Seated in the former and secured by the bonnet B is the steam-nozzle E, of ordinary construction, and in the latter is fitted the lifter combining and delivery tube F F', made of two pieces joined near the middle by screw-threads, as shown. The bore of the upper portion of the tube F is made converging toward the delivery end, and the bore of the lower portion F' is made divergent in the same direction. Within said combining and delivery tube, between the convergent ends of its upper and lower portions, surrounding the convergent end of the former portion, is an annular valve-chamber G', which communicates with the water-chamber C through the passages f f' and the annular groove g, and with the interior of the tube through the space between the adjacent ends of the two portions thereof, said passages f f' being controlled by the automatic annular valve G, which is seated on the inner end of the lower portion of the tube F. (More clearly shown in Fig. 2.)

75 In Fig. 3 the steam-nozzle E and the bore of the combining and delivery tube are substantially the same as those of Fig. 1; but the casing A and the valve G are shown somewhat modified, the former having, in addition to the partitions P T', a third partition T therein, in which is fitted the upper portion of the combining and delivery tube F, and between which partition and partition T' is formed a chamber G', connected with the water-chamber through the aperture g and conduit f, which conduit is formed in the casing over and partially surrounding the water-chamber, and is controlled by the valve G, seated in the aperture g and guided by means of its stem, which fits loosely in the bonnet h, screwed into the casing, which construction affords means whereby easier access to the valve G may be had than is afforded by the construction shown in Fig. 1.

95 In Fig. 4 the steam-nozzle E and the lower portion of the combining and delivery tube F' are shown secured in partitions P and T', respectively, substantially as in Fig. 3, and the upper portion F is loosely fitted in partition T and is provided with an enlargement 100 at its lower end, forming a valve controlling

the longitudinal passages *ff*, made in the exterior of the tube, which passages connect the water-chamber with the chamber *G'* when the pressure in the latter chamber is less than 5 the pressure in the former. When, however, the pressure in chamber *G'* exceeds the pressure in the water-chamber, communication between the chambers through the passages *ff* will be cut off by the enlarged lower end of 10 the movable portion *F*, which will thereby be forced against the valve-seat made therefor in the partition *T*, as is clearly shown in the drawings, the movement of the tube in the opposite direction being limited by the 15 lugs *kk* in such a way that the space between the adjacent ends of the two portions of the combining and delivery tube cannot be entirely closed, a free inlet to the interior of the tube from the water-chamber thus being afforded whenever the valve-surfaces of 20 the tube and of said partition are not in contact.

I am aware that jet apparatus have been made heretofore having a supplemental inlet 25 to the combining-tube, formed by openings through the tube within the water-chamber to increase their delivery; but in all of such jet apparatus, so far as I am aware, such openings lessen the vacuum which the same 30 tubes would produce if they were made continuous—that is to say, without such openings. For example, I found, by experiments made with tubes similar in form and construction to those shown in Fig. 1, that with the valve 35 *G* in the tube the apparatus produced a vacuum of twenty-five inches, (equivalent to lifting water about twenty-eight feet,) its maximum, with fifty-five pounds steam-pressure, and one of eighteen inches (a lift of about 40 twenty feet) with one hundred and thirty pounds steam-pressure, which vacuums are substantially the same that a continuous tube, otherwise of the same internal form and substituted therefor in the apparatus, produced 45 with equal steam-pressure. When the valve *G* was removed, the vacuum at the former pressure was reduced to twenty-two inches (a lift of about twenty-five feet) and at the latter pressure to eleven inches, (a lift of 50 about twelve feet,) showing that the lifting properties of a continuous combining and delivery tube are obtained by means of this invention, together with all of the advantages due to the supplemental inlet.

55 The valve *G*, in the form of apparatus shown in Fig. 3, instead of being automatic in its action may be arranged to be controlled by the attendant—as, for instance, the stem may be lengthened, and a screw-thread 60 formed thereon to work in a corresponding thread in the bonnet *h*, (on which bonnet a stuffing-box should be provided,) and a lever or hand wheel attached thereto. The valve can then be screwed down on its seat

whenever it is desirable to close the supplemental inlet.

I claim as new and desire to secure by Letters Patent—

1. In an ejector, a combining and delivery tube provided at its mouth with the usual inlet for the admission of fluid from the suction-chamber, and provided also with a supplementary inlet formed by one or more ports communicating with the interior of said tube through one or more openings therein 70 and with the suction-chamber, and a valve to automatically close the said supplementary inlet whenever the pressure within the tube at said openings is greater than the pressure in the suction-chamber, substantially as set 75 forth.

2. In an ejector, a combining and delivery tube provided at its mouth with the usual inlet for the admission of fluid from the suction-chamber, and provided also with a supplementary inlet formed by one or more ports 80 communicating with the interior of said tube through one or more openings therein and with the suction-chamber, and a valve to close the said supplementary inlet, 85 substantially as set forth.

3. In an ejector, a combining and delivery tube the bore of the combining portion of which converges from its mouth in the direction of the flow of the fluid through it, provided at its mouth with the usual inlet for the admission of fluid from the suction-chamber, and provided also with a supplementary inlet formed by one or more ports 90 communicating with the interior of said tube through one or more openings therein at or near its throat and with the suction-chamber, and a valve to automatically close the said supplementary inlet whenever the pressure within the tube at said openings is greater than the 95 pressure in the suction-chamber, substantially as set forth.

4. In an ejector, a combining and delivery tube the bore of the combining portion of which converges from its mouth in the direction of the flow of the fluid through it, provided at its mouth with the usual inlet for the admission of fluid from the suction-chamber, and provided also with a supplementary inlet formed by one or more ports 100 communicating with the interior of said tube through one or more openings therein at or near its throat and with the suction-chamber, and a valve to close the said supplementary inlet, 105 substantially as set forth.

In testimony that I claim the foregoing I have hereunto set my hand this 22d day of June, 1888.

CHAS. E. CHURCH.
